UNITED STATES PATENT OFFICE.

FRED L. MACKENZIE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENING-INSERTING MACHINE.

1,313,903.

Specification of Letters Patent. Patented Aug. 26, 1919.

Application filed October 19, 1917. Serial No. 197,495.

To all whom it may concern:

Be it known that I, FRED L. MACKENZIE, a citizen of the United States, residing at Beverly, in the county of Essex and State 5 of Massachusetts, have invented certain Improvements in Fastening-Inserting Machines, of which the following description, in connection with the accompanying drawings, is a specification, like reference characters 10 on the drawings indicating like parts in the several figures.

This invention relates to fastening inserting machines, and is herein illustrated as embodied in a machine for inserting previously formed fastenings into shoe stock of the type shown in the patent to Goddu, No. 1,030,775, granted June 25, 1912, to which patent reference may be made for a complete disclosure of various parts not fully described herein.

The fastening inserting mechanism of machines of this type comprises a driver for forcing the fastenings into the stock, a fastening receiving member having a passage formed therein to receive the driver, and a raceway for supplying fastenings to the fastening inserting mechanism. The delivery end of the raceway is spaced from the fastening receiving member a sufficient 25 distance to permit means, commonly denominated a separator, to pass between them. The separator operates to select the fastenings one by one from the raceway and move them to the passage in the fastening receiving member. A part is integrally formed on the delivery end of the raceway for conveying the fastenings across the space between the delivery end of the raceway and the fastening receiving member to 30 the passage in the fastening receiving member.

Although such construction has proved to be in the main satisfactory there are some disadvantages attendant to its use. It is 45 desirable that the upper or fastening supporting surface of the part on the delivery end of the raceway be located as close as possible to the top of the separator which passes beneath it in order that the separator 50 may be caused to engage the fastenings as near to the heads thereof as possible to enable the separator to move bodily into the

passage of the fastening receiving member without pivotal movement about their heads, such as results if the separator engages the 55 fastenings too near their pointed ends. For this reason it is necessary to aline the raceway carefully with the fastening receiving member, and to that end the delivery end of the raceway and the part formed thereon are 60 carefully finished and ground after being cast. If the delivery end of the raceway or the part formed thereon is inaccurately ground so as not to properly coact with the fastening receiving member or with the separator, the 65 entire raceway must be scrapped. In machines in which the raceway is formed to provide a plurality of sources of fastening supply, the raceway and the fastening receiving member are shiftable relatively to 70 each other so as to bring either of the sources of fastening supply of the raceway into operative relation with the passage of the member. The raceways of such machines must be finished off with excessive care, and even then 75 it often happens that the fastening conveying part on the delivery end of the raceway is bent or broken, thus rendering the entire raceway useless.

An object of the present invention is to 80 provide improved mechanism for delivering fastenings from a raceway or the like to fastening inserting mechanism which, while retaining important advantages of known constructions, will be free from the above- 85 mentioned and other disadvantages.

An important feature of the invention consists in providing the fastening receiving member of the fastening inserting mechanism, with a part extending in the 90 direction of and to a point adjacent to the plane end surface of the raceway, the raceway being formed to present a substantially horizontal fastening supporting surface at its end and said part operating to guide and convey the fastenings from the end of the raceway to the passage of the fastening receiving member. In accordance with a further feature of the invention, a guiding member is provided independent of the above-mentioned part for guiding the fastenings in their passage from the raceway to the fastening receiving member. Said guiding member is preferably

spaced from the above-mentioned part a sufficient distance to receive the separator between them.

When mechanism constructed in accordance with the present invention is used, the raceway can be initially cast in a form requiring very little finishing to prepare it for use on the fastening inserting machine, and can thus be manufactured easily and cheaply, whereas the raceway as heretofore constructed required a considerable amount of grinding and finishing after the casting was formed, making its manufacture relatively difficult and costly. Moreover, if in the use of the present construction, the part which guides and conveys the fastenings from the delivery end of the raceway to the fastening inserting mechanism is rendered unfit for use, thus necessitating the substitution of a new part, the expense involved is much less than that entailed by the substitution of a new raceway.

In accordance with a further feature of the invention, a raceway formed to provide a plurality of sources of fastening supply is pivoted at a point removed from the fastening receiving member and has its end surfaces formed at an acute angle to its center line or axis on each side of the axis to permit the end surface of the raceway at either side of the axis to be brought into a position parallel to and in close engagement with the end of the part which guides the fastenings from either of the sources of fastening supply of the raceway to the fastening receiving member.

Although the invention is illustrated and described as embodied in the type of fastening inserting machine shown in the patent to Goddu No. 1,030,775, it is recognized that the invention, or various features thereof, may be used in other machines, and that the invention is limited only by the scope of the appended claims.

Other objects and features of the invention will be apparent as the description proceeds.

In the drawings,

Figure 1 is an end view illustrating parts of a fastening inserting machine embodying the features of the invention with a portion of the hopper for the fastenings broken away to reveal the structure within;

Fig. 2 is a plan view partly in section of the parts shown in Fig. 1; the section through the driver guide being taken on line 2—2 of Fig. 1, and the raceway being shown with the cover-plates of the slots removed;

Fig. 3 is a plan view of the delivery end of the raceway and the parts associated therewith but illustrating the inner slot of the raceway in operative relation to the fastening receiving passage of the driver guide;

Fig. 4 is a plan view of parts correspond-

ing to those shown in Fig. 3 but illustrating a single raceway construction;

Fig. 5 is a detail view of the driver guide showing a modified construction thereof from that shown in Figs. 1, 2, 3 and 4;

Fig. 6 is a detail view of the detachable plate which constitutes the upper lug of the driver guide;

Fig. 7 is a broken view showing a modified construction of the end of the raceway and of the upper lug of the driver guide, and

Fig. 8 is a broken view showing a still further modification of the raceway and driver guide.

The numeral 2 designates the bracket of a fastening inserting machine which carries the receptacle 4 for the fastenings and the raceway 6 which supplies the fastenings to the fastening inserting mechanism at the delivery end of the raceway, the bracket 2 being mounted upon the frame of the fastening inserting machine in the usual manner (not shown).

The raceway 6 is preferably formed to provide a plurality of sources of fastening supply. As shown in Figs. 1 and 2, two sources of fastening supply are provided comprising fastening receiving slots diverging from the delivery end of the raceway toward its upper end which passes into the receptacle 4, said receptacle embodying two rotatable hoppers 10 and 12 provided with vanes 14 which raise the fastenings as the hoppers are rotated and deliver them upon shelves 16 extending from the end of the raceway, as shown clearly in Figs. 1 and 2 of the drawings. The hoppers are rotated by gearing 18 in the usual manner and shields 20 are provided in each of the hoppers to overlie the slots in the raceway and remove any fastenings which are not properly positioned in the slots of the raceway. The construction thus far described is illustrated and described in the patent to MacKenzie, No. 1,225,837, granted May 15, 1917, and forms no part of the present invention, for which reason a more complete description of the same is deemed unnecessary.

Referring particularly to Figs. 1 and 2 of the drawings, there is provided a fastening receiving member 8 which has a passage 24 to receive the fastenings and which also acts as a guide for a driver 26 to insert the fastenings into the work. As illustrated, the end surface 28 of the raceway 6 is a plane end surface. In other words, the raceway has all portions of its end surface substantially in the same plane and the cover-plate 22 of each of the slots of the raceway extends beyond the end of the raceway and overlies a portion of the upper lug or projection 30 of the driver guide which extends beyond the fastening receiving passage 24 of the driver guide in the direction of the end of the raceway. The lug 30 is formed with a

slot 32 which is adapted to be alined with the slot or slots of the raceway to receive the fastenings from the slot of the raceway and to guide and convey the same to the passage 5 of the driver guide. The portion of cover plate 22 which extends beyond the end of the raceway and over the slot of the lug 30 to a point adjacent the passage of the driver guide assists in guiding the fastenings from 10 the end of the raceway to the passage of the driver guide. Means are provided for moving the fastenings one by one along the slot of the lug 30 to the passage of the driver guide in the form of a separator 34 having 15 a part 36 which moves in a passage defined on one side by the wall of the driver guide, on the other side by the end wall 28 of the raceway, at the top by the lug 30, and at the bottom by a second lug 38 formed on the 20 driver guide. The lug 38 prevents the pointed ends of the fastenings from being moved laterally by the separator and assists in guiding the fastenings to the passage 24.

The raceway is movable by connections 25 with a rod 40 from the position shown in Fig. 2 to and from the position shown in Fig. 3. The rod 40 may be operated in any suitable manner, (not shown), the operating means therefor forming no part of 30 the present invention.

Referring to Figs. 2 and 3 of the drawings, it will be seen that the end surfaces of the raceway on each side of its axis as indicated at 42 and 44 are formed at an 35 angle to the center line or axis of the raceway slightly less than a right angle to permit pivotal movement of the raceway on its fulcrum 46 so that either of the slots of the raceway may be alined with the slot 40 32 in the lug 30 of the driver guide. The degree of the angle is so related to the distance from the delivery end of the raceway to its fulcrum 46 as to permit the lugs on the driver guide to be brought into close 45 association with either of the end surfaces of the raceway as is essential to the proper transfer of the fastenings from the raceway to the lug 30 of the driver guide.

In Fig. 2 of the drawing the outer slot is 50 shown in operative relation to the passage of the driver guide, the fastenings in the inner slot being retained by engagement with the lug 30 on the driver guide and with the separator. Fig. 3 shows the inner slot 55 of the raceway in operative relation to the passage of the driver guide, the fastenings in the outer slot being retained by engagement with the lug on the driver guide. I am enabled to utilize the lug on the driver 60 guide as a retainer for the fastenings in the outer slot by extending it beyond the separator in the direction of the end of the raceway whereby it restrains the fastenings in said slot from movement into the path of 65 movement of the separator.

The parts shown in Fig. 4 are arranged similarly to the parts described, it being noted, however, that in said figure is illustrated an embodiment of the invention comprising a raceway 106 having a single slot 70 only which alines with the slot 132 of the upper lug 130 of the driver guide 108. The separator 134 operates in the manner previously described to move the fastenings one by one along the lug 130 to the passage 75 124 of the driver guide 108.

In Figs. 5 and 6 is shown a modification of the driver guide applicable to use with either the double raceway illustrated in Figs. 1, 2 and 3, or with the single raceway 80 as illustrated in Fig. 4. In the modification, the upper lug instead of being integrally connected to the driver guide as in the constructions illustrated in Figs. 1, 2, 3 and 4, is in the form of a plate 230 detachably connected thereto by means of screws 48 and 50. With reference to Fig. 6, it will be noted that the plate 230 constituting the upper lug has a widened portion 52 provided with an opening 54 to receive the screw 48 and a slot 232 to receive a fastening from the slot or slots in the raceway, and a reduced portion 54 forming a shoulder 56 which abuts against the end wall 58 of a groove formed in the driver 95 guide at right angles to the fastening receiving passage. The slot 232 of the plate 230 is enlarged at 233 to form an opening alining with the passage 224 of the driver guide. The screw 50 is formed with a head 100 which abuts against the edge of the reduced portion 54 of the plate 230, thus securing the same firmly in position. If the detachable plate 230 on the driver guide becomes bent or broken, it can be replaced 105 with little trouble or expense.

Fig. 7 illustrates a still further modification of the invention, involving differences in the construction both of the raceway and driver guide from the devices previously 110 described. The upper surface of the raceway 306 is recessed at the delivery end of the raceway as indicated at 60, and the driver guide 308 is provided with the upper lug 330 and lower lug 338 extending therefrom in the direction of the end of the raceway. As illustrated the upper lug 330, which is in the form of a plate detachably connected to the driver guide in the manner shown in Figs. 5 and 6, is extended to 120 lie in the recess 60 in the end of the raceway. In this construction, the upper lug 330, the upper surface of which lies in the same plane with the upper surface of the raceway to the rear of the recess 60, receives 125 the fastenings before they have left the raceway.

A still further modification of the invention is illustrated in Fig. 8, which construction embodies a driver guide 408 hav- 130

ing a lug 430 extending therefrom in the direction of the raceway as in the constructions previously described. In this construction, however, the lower lug 438 which, 5 in connection with the upper lug, forms a passage-way through which passes the upper section 436 of the separator, is provided at the end of the raceway 406 rather than on the driver guide, as in the constructions 10 previously described.

Having described the invention, what I claim as new and desire to secure by Letters Patent of the United States is:

1. In a machine of the class described, in 15 combination, a raceway having a plane end surface and a fastening supporting surface arranged in a horizontal plane, a driver, a driver guide provided with a passage to receive a previously formed fastening and to receive said driver, a part extending from said driver guide in the direction of and to a point closely adjacent to the plane end surface of the delivery end of the raceway, said part having its upper 20 surface substantially in the same horizontal plane as the upper fastening supporting surface of the delivery end of raceway and being slotted to receive a previously formed fastening from the raceway and to support 25 and guide it to the passage in the driver guide, and means for moving the fastenings one by one along said part to the passage in the driver guide.

2. In a device of the class described, in 35 combination, fastening inserting mechanism, a raceway provided with a source of fastening supply for supplying fastenings to the fastening inserting mechanism, and having a plane end surface and a fastening supporting surface arranged in a horizontal plane, said fastening inserting mechanism comprising means for forcing the fastenings into the work and a fastening receiving member provided with a fastening supporting 40 surface also in a horizontal plane and having a passage to receive said means and having a slotted projection extending therefrom in the direction of the plane delivery end of the raceway to guide the fastenings 45 from the raceway to said passage, and means underlying the projection for moving the fastenings guided by the projection to said passage.

3. In a machine of the class described, 55 fastening inserting mechanism, and a raceway for supplying fastenings to the fastening inserting mechanism provided with a plane end surface and arranged to be stationary during a plurality of cycles of operations of the machine, said fastening inserting mechanism comprising a fastening separator and a fastening receiving member spaced from the delivery end of the raceway, and means on said fastening receiving member for supporting and guiding the fasten-

ings from the raceway to said member, comprising spaced projections extending into contact with said plane end surface of the raceway and designed to guide said separator.

4. In a machine of the class described, in combination, fastening inserting mechanism comprising means for forcing the fastenings into the work and a fastening receiving member formed with a passage to receive 70 said means, said member having projections extended therefrom, slotted to permit the passage of previously formed fastenings into said passage, one of said members being constructed and arranged to support the fastenings by engagement with the heads thereof, a raceway having a plane end surface arranged to abut against said projections, and means for moving the fastenings one by one from the raceway and through the 75 slots of said projections into said passage.

5. In a machine of the class described, in combination, a raceway having all portions of its end surface substantially in the same plane, a driver, a driver guide provided with a passage to receive previously formed fastenings and to receive said driver, said driver guide being spaced from the end of the raceway and having projections extending therefrom in the direction of and adjacent to the end of the raceway, and means 80 operating between said projections for moving the fastenings one by one to the passage in the driver bar.

6. In a machine of the class described, in 100 combination, fastening inserting mechanism comprising means for forcing the fastenings into the work and a fastening receiving member provided with a passage to receive said means, said member having a plate extending therefrom and detachably secured thereto provided with an opening in alignment with the passage and with a slot constructed and arranged to support previously formed fastenings and guide the same to 105 the passage of said member, and means for moving the fastenings one by one along said slot and into said passage.

7. In a machine of the class described, in combination, a raceway, fastening inserting 110 mechanism comprising a fastening receiving member provided with a passage to receive previously formed fastenings, said member having a groove formed therein substantially at right angles to said passage, a plate 115 removably secured in said groove provided with an opening in alignment with said passage, said plate projecting from said member in the direction of and to a point adjacent to the end of the raceway and constructed 120 and arranged to support and guide the fastenings from the raceway to the passage in said member.

8. In a machine of the class described, in combination, fastening inserting mechanism, 130

means for supplying fastenings thereto, said fastening inserting mechanism comprising a fastening receiving member provided with a passage to receive previously formed fastenings, and having a groove formed therein substantially at right angles to said passage, a plate removably secured in said groove provided with an opening in alignment with said passage and constructed and arranged 5 to guide the fastenings from the fastening supplying means to said member.

9. In a machine of the class described, in combination, fastening inserting mechanism, means for supplying fastenings thereto, said 10 fastening inserting mechanism comprising a fastening receiving member formed with a passage to receive the fastenings, and provided with a groove substantially at right angles to the passage, a plate removably secured in the groove and provided with a reduced portion extending beyond the end wall of the groove forming a shoulder on the plate adapted to engage the end wall of the groove, and means co-acting with the 15 reduced portion of the plate to secure the same in position on said member, the plate being constructed and arranged to receive fastenings from the fastening supplying means and to support and guide them to the 20 passage in said member.

10. In a machine of the class described, fastening inserting mechanism and a raceway for supplying fastenings to the fastening inserting mechanism, said fastening inserting mechanism comprising a fastening receiving member having a part extending in the direction of and overlying the delivery end of the raceway to guide the fastenings from the raceway to said fastening receiving 25 member.

11. In a machine of the class described, in combination, fastening inserting mechanism, a raceway for supplying previously formed fastenings to said fastening inserting mechanism, said fastening inserting mechanism comprising means for forcing the fastenings into the work and a fastening receiving member having a passage to receive said means and having a part extending therefrom constructed and arranged to overlie the end of the raceway and to receive fastenings from the raceway and to support and guide them to said passage.

12. In a machine of the class described, in combination, fastening inserting mechanism, a raceway for supplying previously formed fastenings to the fastening inserting mechanism, said fastening inserting mechanism comprising means for forcing the fastenings into the work and a member formed with a passage to receive the fastenings and to receive and guide said means, said member having a projection extending therefrom in the direction of and beyond the end of the 60 raceway, the raceway being formed with a 65

cut-away portion adjacent the end thereof constructed and arranged to receive the end of the projection with the upper surface of the projection substantially in alignment with the upper surface of the raceway, the 70 projection being constructed and arranged to receive the fastenings from the raceway and to support and guide them to the passage in said member.

13. In a machine of the class described, fastening inserting mechanism comprising a fastening receiving member and a raceway for supplying fastenings to the fastening receiving member formed to provide a plurality of sources of fastening supply and 75 movable relatively to said member and having a delivery end all portions of which are in the same plane, said member having two projections extending into close proximity to the delivery end of the raceway 80 and constructed and arranged to support and guide fastenings from either of the sources of fastening supply of said raceway to said fastening receiving member.

14. In a machine of the class described, in combination, a raceway, fastening inserting mechanism comprising means for forcing the fastenings into the work and a fastening receiving member having a passage formed therein to receive and guide said means and 90 having a projection formed with a slot communicating with said passage extending therefrom in the direction of and adjacent to the end of the raceway, the raceway being pivoted at a point removed from said 95 member and having its end surfaces formed at an acute angle to its axis on each side of the axis to permit the end surface of the raceway at either side of the axis to be brought into a position parallel to and in 100 close engagement with the end of the projection, the raceway being provided with sources of fastening supply on opposite sides of its axis adapted to align with the slot of 105 said projection.

15. In a machine of the class described, in combination, fastening inserting mechanism comprising a fastening receiving member, a pivotally mounted raceway for supplying fastenings to said member provided with 110 sources of fastening supply on opposite sides of its axis and having its end surfaces formed at an acute angle to the axis of the raceway, the degree of said angle being so related to the pivotal point of the raceway 115 as to permit the end surface of the raceway at either side of its axis to be brought into a position parallel to and in close engagement with said member with the source of fastening supply on that side of the race- 120 way in operative relation to said member.

16. In a machine of the class described, in combination, a raceway provided with two slots to receive previously formed fastenings, a fastening inserting mechanism compris- 125 130

ing a member having a passage toward which the fastenings are conveyed in said slots, said member having a projection extending therefrom provided with a slot arranged to align with either of the slots of said raceway and to guide the fastenings from the slots of the raceway to the passage of said member, the slots of the raceway being formed on opposite sides of the axis thereof and the end surfaces of the raceway on both sides of its axis being formed at an angle to the axis slightly less than a right angle to permit the end surface of the raceway in which either slot is formed to be brought into a position parallel to and in close engagement with the portion of the edge of said projection in which said slot is formed with the slot of the raceway in alignment with the slot of the projection.

17. In a machine of the class described, in combination, fastening inserting mechanism, a raceway having all portions of its delivery end surface in the same plane and formed with a plurality of sources of fastening

supply for supplying the fastening inserting mechanism, said fastening inserting mechanism comprising a fastening receiving member having a slotted projection extending therefrom with its upper surface in the same plane as the fastening supporting surface of the delivery end of the raceway, the raceway and said member being relatively movable to position any of the sources of fastening supply of the raceway in operative relation with the slot of the projection, means underlying the projection for moving the fastenings along the projection to said member, the distance from the slot of the projection to its end being greater than the distance between the sources of fastening supply of the raceway to cause said projection to retain the fastenings in one slot from movement into the path of said means when another slot is in operative relation to said means.

In testimony whereof I have signed my name to this specification.

FRED L. MACKENZIE.

Copies of this patent may be obtained for five cents each, by addressing the "Commissioner of Patents, Washington, D. C."
